5 Claims.

(Cl. 9—2)

This invention relates to improvements in collapsible boats.

The framework of folding boats usually consists of rigid shapes which are fastened together to make a boat shape. To set the boat up these shapes are attached to each other by screws or other couplings, the rigid ribs and keel usually stipulating the form of the boat. When the frame has been erected a separate cover of some waterproof fabric is drawn over it and made taut. To take the boat down the covering is taken off, the screws or other connections loosened and the members of the frame taken apart, or folded upon themselves by hinges, and the various components put away in a duffle bag or knapsack, or bound together in a bundle. To set up such a boat usually requires from twenty to thirty minutes.

The principle of having a frame made of several separate parts which are put together when it is desired to use the boat and are separated again to enable it to be packed into a small space is not applied in this invention. In this invention the frame is made of full length longitudinal and transverse members formed from strips of pliable resilient material joined to each other permanently and having a cover and deck permanently attached to it. The object of my invention is that a boat may be so made that it may be rolled up complete—i. e., with the deck and cover still attached to the frame in their proper place—along its length from either end into a small space when it is desired to pack it or carry it. The only operation required before the boat when set up can be so rolled is to unfasten a connection between the two longitudinal halves of the deck. When rolled the boat is secured by a strap around its circumference, to hold it against the stress of the resilient frame. To set up the boat the strap is unfastened and the boat unrolls itself by virtue of the frame's resilience into what is later in this specification described as "the first state." The deck is then stretched by closing its central longitudinal opening by a fastener, bringing the boat into its shape for use. The whole process of setting up takes only from thirty to forty seconds as contrasted with the twenty to thirty minutes consumed by setting up other kinds of folding boats.

In the annexed drawings Figure 1 is a plan of the frame. Figure 2 is a profile of the frame. Figure 3 is a general view of the frame, partly rolled up on itself. Figure 4 is a general view of the complete boat. Figure 5 is a section of the complete boat when rolled up. Figure 6 is a sec-

tional view along lines $x-x$, Fig. 1, but with a cover loosely in place. Figure 7 is a sectional view along line $y-y$, Fig. 4. Figure 8 is an enlarged section of the upper part along the same number as in Fig. 6, showing details of the gunwale reinforcement. Figure 9 is an enlarged section of the upper part along the same section as in Fig. 7, showing details of the gunwale reinforcement. Figures 10 and 11 are sectional views of modifications of gunwale reinforcements taken along line $x-x$, Fig. 1.

The frame is so designed that it assumes three states. The first state, Figs. 1 and 2, it takes naturally upon construction or release from either of the other two states. The second state—15 section Fig. 5—is assumed when the frame in its first state is rolled up and confined in the roll against its resilience. The third state, Fig. 4, is that which it assumes when the edges are drawn towards each other and secured by a deck and so made into a rigid hull, the deck being made taut by and straining against its resilience.

The frame is made of thin strips of material that must combine strength with lightness and thinness and must be both pliable and resilient. 25 The same material is used throughout the frame. The strips may be of wood of sufficient pliability for the frame to be rolled up lengthways—I prefer to use strips of split bamboo—or it may be of steel or other metal. Long strips to a sufficient 30 number form the longitudinal members and run the full length of the boat, as shown in the Figures 1 and 2, where they are marked 1. The transverse members 2 are shorter strips to a sufficient 35 number laid across them and rigidly and permanently secured to them by any convenient fastening. The length of the individual longitudinal and transverse members is such that when the frame is made it has the shape of a shallow trough rising towards the pointed ends 40 with evenly curving sides. Its outline is that of Figure 1, and its profile is shown in Figure 2. Figure 6 shows a section along half the transverse member marked $x-x$ in Figure 1 when in this state.

This frame can, by virtue of its form and the pliability of its members, be rolled upon itself from end to end into a small space without disturbing the relationship of the members to each other. The frame (without covering and gunwale reinforcement) is shown partly rolled in Figure 3.

When it is desired that the frame take the shape of a hull, as in Figure 4, the edges are drawn up and towards each other and held there by a deck 3 made fast to each edge. When this 55

has been done the shallow trough of Figures 1 and 2 has become narrower and deeper—a section along the same transverse member, as Figure 6, in this state is shown in Figure 7—while the 5 pointed ends may be still higher than the edges or gunwales amidships as in Figure 4. For convenience the edges of the deck are permanently fastened to the gunwales and the deck itself cut along the longitudinal centre line of the boat; the 10 edges of this severance are secured together when it is desired to use the boat by means such as shall later be described.

Although the boat may be made with the cover or skin entirely apart from the frame, in which 15 case it must be placed over the frame after it has been brought to the proper shape, it is desirable, and a special object of this invention permanently to secure the cover to the frame, so that cover, frame and deck are rolled up together and there 20 is no separate packing of them. Figure 5 shows section of the complete boat—frame, deck and cover—in its rolled up, or second state.

The cover 4 may be of canvas or other fabric which may be strengthened or finished with rubber, lacquer or paint. "Rubberized canvas" may 25 be usefully employed. It is cut on the bias so that it may take the proper shape of the frame and is secured to the frame. The outer edges of the two portions of the deck 3, also of canvas or 30 fabric, are secured to the frame in the same place as the cover 4. This is done as shown in details in any of the Figures 8, 9 or 10. 3 is the deck, 4 the cover. The edges of deck and cover are 35 sewn together and together secured by heavy stitches 12 to a chafing strip 9 of heavy braided cord which is itself secured along the gunwale with the same stitches 12. This chafing strip 9 runs the full length of the boat and serves both to secure the cover and deck to the frame and to protect the deck from chafing where its pressure is on the frame, as shown in Figures 9, 10 and 11.

To prepare the boat for use the two portions of the deck 3 are brought together until they meet 45 in the centre by applying some continuous fastener 5 such as a slide fastener as shown in Figures 4, 5, 6 and 7.

When the deck has been stretched the complete 50 boat forms a girder rigid in all directions. As in a basket a rigid band around the edge confines the pliable withes of which it is made into a rigid form so the tension of the deck against the resilience of the members of the frame confines them into rigidity.

However, as the deck is of fabric and has no 55 wooden or metal supports or braces there might occur some slight distortion of the gunwales and hence of the boat. To prevent this I do two things. First; the fabric of the deck is cut on the bias to the centre line, so that the individual threads 6 of the fabric act as tensional braces as shown in Figure 4. Second; it is a special object of this invention to strengthen and support the gunwale as follows. Figures 8 and 9 60 show the gunwale reinforcement in its two positions. These figures are enlarged sections of Figures 6 and 7 respectively, showing details of the gunwale reinforcement. Figure 8 shows the member in the first and second state of the frame, Figure 9 in the third state. At the ends of the transverse members 2 fabric or leather loops 7 are fastened to the gunwale tightly fitting 65 over the reinforcing strip 8 of the same material.

as the frame and having a section as shown. It runs the full length of the boat. When the boat is in either the first or second state this strip lies back as in Figure 8 and is rolled up with the frame as shown in Figure 5. When the boat is used the deck 3 is stretched over it, bringing it to the position shown in Figure 9 and jamming it tightly at an angle against the gunwale. This angle gives such rigidity as prevents distortion. 70

Another method of preventing distortion of the gunwale is by stiffening the fabric of the deck in a strip along its edge with some stiff material. This may be done by applying a strip of lacquer to the deck, as shown in Figure 10, where 10 is a strip of lacquer applied to the deck 3 when 15 stretched, which, having impregnated the fabric and dried hard, acts in the same way as the reinforcing strip of Figures 8 and 9.

It is a special quality of a boat built as described that the cover may not only be made of 20 soft materials such as fabric or rubber, but also of any stiff or hard materials having the necessary form and flexibility. Thus a canvas cover may be lacquered to a hard finish and so become more durable and satisfactory. The cover may 25 also be of thin metal, which is brought to the correct shape—that of the frame in its first state—by any of the usual means of shaping sheet metal, such as panel beating or by means of a rolling mill having appropriate rollers. Figure 11 shows 30 a part section along the same transverse member as Figure 7 illustrating the use of a hard cover 11.

What I claim is:

1. A collapsible boat consisting of a frame of 35 flexible and elastic members permanently fastened together, said frame having a heavy braided cord permanently attached to the gunwales, a deck divided in two portions and a cover both being permanently secured to said cord in such 40 manner that said cord acts as a permanent connection between deck, cover and frame, and acts also as a chafing strip between the deck and the frame, said deck, frame and cover being rolled up together to pack the boat. 45

2. A frame for a collapsible boat consisting entirely of strips of flexible material, certain of 50 said strips extending longitudinally of the frame entirely from end to end thereof, others of said strips extending transversely of the frame and entirely from side to side thereof, means joining the respective ends of the longitudinal strips together at common points, means rigidly interconnecting the longitudinal and transverse strips at the points of intersection whereby the frame may 55 be rolled upon itself.

3. The frame as claimed in claim 2 wherein 60 means are provided for interconnecting the side longitudinal strips whereby said frame is constrained to maintain the form of a boat.

4. The frame as claimed in claim 2, wherein 65 fabric deck means is provided extending between and interconnecting the side longitudinal strips and wherein said fabric is connected to the said frame on the bias providing a multitude of tensional cross braces whereby the frame is rigidly constrained in the form of a boat.

5. The frame as claimed in claim 2 including 70 deck means extending between and interconnecting the side longitudinal strips and reinforcing means along the interconnection between the side strips and the deck means.

GUENTHER WERNER.
